UNITED STATES PATENT OFFICE.

FRANKLIN W. LANTZ, OF WASHINGTON, DISTRICT OF COLUMBIA.

MAGAZINE-GUN.

SPECIFICATION forming part of Letters Patent No. 477,128, dated June 14, 1892.

Application filed January 27, 1892. Serial No. 419,446. (No model.)

To all whom it may concern:

Be it known that I, FRANKLIN W. LANTZ, a citizen of the United States, residing in the city of Washington, District of Columbia, 5 have invented certain new and useful Improvements in Firearms, of which the following is a specification.

My invention relates to breech-loading firearms in which the breech is opened and closed 10 by a longitudinally-reciprocating bolt.

It relates more especially to manually-operated magazine-firearms in which the cartridges are arranged laterally in a magazine-chamber below the breech-bolt and are successively fed to a firing-chamber during the reciprocating movements of the bolt.

The principal objects of my invention are to provide for the automatic closing of the breech when there is a cartridge in the receiver, to provide for automatically locking the breech mechanism open when the receiver is empty, to provide for the automatic feeding of the cartridges from the magazine to the axial line of the barrel, and to insure the 25 automatic upward expulsion of the cartridge-holder after it has been emptied.

The details of construction and the subject-matter claimed are hereinafter set forth and designated.

30 The accompanying drawings show so much of the mechanism of a breech-loading magazine-firearm as is deemed necessary to illustrate my invention. I have shown my improvements embodied in the best way now known to me. Obviously, however, some of my improvements may be used without the others, and the details of construction and some parts of the mechanism may be modified in various ways without departing from 35 the novel features of my invention.

Figure 1 is a side elevation of the breech portion of a gun constructed according to my invention. Fig. 2 is a vertical longitudinal central section, some of the parts being shown 40 in elevation and the mechanism being shown as it appears immediately after firing. Fig. 3 is a similar view, the mechanism being shown in the position it assumes just before a cartridge is fed to the firing-chamber. Fig. 4 is 45 a longitudinal transverse section on the line 44 of Fig. 2. Fig. 5 is a detail view in section showing the mechanism half-cocked.

Fig. 6 is a similar view with the parts in full-cock position. Figs. 7, 8, 9, and 10 are respectively cross-sections on the lines 77, 88, 55 99, and 1010 of Fig. 2. Fig. 11 is a detail view, partly in section, showing the breech-bolt locked back by the carrier. Fig. 12 is a detail view in cross-section to show the guide for a lug on the sear. Fig. 13 is a side elevation, Fig. 14 a rear end view, Fig. 15 a vertical section, and Fig. 16 a transverse section, of the cartridge holder or case.

The stock A is suitably recessed and grooved to contain the operating mechanism, and the breech end of the barrel B is provided with a firing-chamber B', as in other guns of this class. The receiver C, which is secured at its front end to the barrel and extends backwardly a suitable distance on the stock to accommodate the breech-bolt, is formed with an opening c, through which the cartridges are admitted and ejected, and it is open along the bottom from its rear end to the end of the barrel. The rear end of the receiver is provided with extensions C', which are secured to the stock, as shown in Fig. 4.

A magazine-chamber D, closed at bottom by the casing d, is arranged immediately below the front end of the receiver. The casing d 80 extends rearwardly and is bifurcated at d', the arms d' extending rearwardly and downwardly along the bottom of the stock. The receiver and the casing d, with its bifurcated extensions d', may be secured to the stock in 85 any suitable way. The carrier is shown as consisting of a table d¹, a curved lever-arm d², and a spring d³. The lever-arm d² is pivoted at one end to the casing of the magazine and at its opposite end is pivotally connected 90 to the cartridge table or feeder d⁴, which bears against the under side of the lowermost cartridge in the series. The spring d³, which is secured to the casing d, bears against the lever d² and tends to move the table vertically 95 to feed the cartridges successively into position in front of the bolt, by which each cartridge is inserted into the firing-chamber. The arrangement is such that the cartridges are fed successively directly into the line of 100 fire, so that the forward movement of the bolt moves a cartridge in the axial line of the barrel directly into the firing-chamber.

The cartridges are carried in a case, holder,

- or packet E of a novel construction. (Shown in detail in Figs. 13 to 16, inclusive.) The case is preferably made of suitable sheet metal and is formed with inclined front and rear edges. The sides are closed and the case is open at each end and at bottom. At top the case is provided with an opening or chamber e, closed at top, into which a cartridge is fed just before it is inserted into the firing-chamber. The chamber e is open only at the bottom and at each end. A cartridge may thus be fed into it from below and moved laterally from it, but cannot be moved upwardly beyond the axial line of the firing-chamber. The lower edges e' of the case are turned inwardly slightly, and one of the rear edges is provided with a notch e² to receive a retaining-catch, hereinafter referred to. A cross-piece e³ serves to prevent the two sides of the case from spreading too far apart. It also forms a bearing or abutment for the carrier when the carrier is actuated to eject the case from the receiver. Flanges or ribs e⁴, formed on the sides of the case, fit in corresponding grooves in the receiver and the magazine-chamber and prevent any movement of the case other than its substantially vertical movement in being inserted and expelled from the magazine.
- A catch F, pivoted at its lower end f in the magazine-chamber, is provided with a rearwardly-extending finger-piece f' and at its upper end with a tooth or hook f², which engages with the notch e² in the cartridge-case when it is in position in the magazine. A spring f³, which may be an extension of the spring d⁵, bears against the catch and tends to move it into engagement with the case. The ribs e⁴ of the case are formed with corresponding interior grooves e⁵, and in these grooves the rims of the cartridges lie.
- As is clearly seen in Figs. 2 and 3, the cartridges have only about one-third of their bodies within the case, this being sufficient for all purposes.
- When the bolt is retracted and there is no packet of cartridges in the magazine, the carrier d³ bears, by means of its shoulder d⁶, against the shoulder b of the receiver C, near the rear end of the barrel. The opposite end of the carrier bears against the front end of the bolt, as shown in Fig. 11, the carrier being provided with a shoulder, as there illustrated, to engage the end of the bolt.
- A packet of cartridges may be inserted by pressing the lower end of the case against the table d⁴, which is thereby depressed, the case then sliding against the front end of the bolt, through the receiver, and into the magazine-chamber, being guided during this movement by grooves in the side walls thereof. The construction and operation of this part of the mechanism will be further described herein-after.
- The trigger-guard G is secured to or formed with a sliding bar G', having suitable bearings in the guide-easing G². A coiled spring

G³, housed in a casing in the stock, bears against the rear end of the slide G' and normally holds it in its front position and returns it to this position when moved out of it and when free to act. The trigger I extends through the casing G² and through a mortise in the slide G', being pivoted at i in the slide. The inner end of the trigger extends forwardly and upwardly, being formed with a hooked end i' for operating the firing mechanism. The slide is formed at its upper front end with a hook g and a laterally-projecting lug or stud g'. It is also formed with a longitudinal groove g², which connects with an upwardly and backwardly inclined groove and slot g³, the grooves and slot forming a cam for operating the breech-bolt abutment herein-after referred to.

The breech-bolt K is adapted to reciprocate without turning within the receiver. The rear end of the receiver is open at k and the bolt is adapted to pass through this opening and extend rearwardly therefrom, as shown in Fig. 3. An arm K', secured to or formed with the breech-bolt, extends through the open bottom of the receiver. It is provided with a slot vertical at k' and extending upwardly and forwardly at k². Into this slot extends the lug or stud g' on the upper end of the trigger-guard slide. A vertically-sliding abutment L is adapted to move in guides in rear of the breech-bolt. The abutment is slotted at l to accommodate the stem of the firing-pin. A downwardly-extending arm l' of the abutment is provided with a laterally-projecting lug or stud l², engaging the cam-slot and groove in the trigger-guard slide. As the trigger-guard slide is reciprocated, the abutment is moved vertically at the proper times.

The breech-bolt is formed of a single piece of metal. It is perforated from end to end, being formed with suitable chambers for the firing-pin and its operating mechanism. The front end of the firing-pin M works through a screw-plug m and is operated by a coiled spring m'. The rear end or stem m² of the firing-pin extends beyond the rear end of the breech-bolt and is provided with a finger-piece M'. A sear M³ is pivoted in the firing-pin, and its front end is adapted to engage with a shoulder m³ of the bolt. Its downwardly-projecting arm m⁴ is adapted to engage with the front end of the trigger. The sear is provided with a lug m⁵, which rides along a flange or rail m⁶ in the receiver, by which arrangement the sear is prevented from turning on its pivot, except when the breech-bolt is closed and in firing position, the rail being cut away immediately in rear of the magazine-chamber to accommodate the proper movement of the sear. A shoulder m⁷ on the firing-pin is adapted to receive the upper hooked end of the trigger when it is desired to half-cock the gun.

The extractor N is arranged in a suitable recess n in the receiver and is operated by the breech-bolt. As shown in Fig. 4, the ex-

tractor is provided with a heel n' , which projects into a recess n^2 in the bolt. When the mechanism is in the position shown in Fig. 4, which is as it appears at the instant after firing, the bolt may have a backward motion for a considerable distance before the extractor is operated. After moving through this distance the shoulder n^3 on the bolt comes in contact with the heel n' of the extractor, which is then moved a sufficient distance to extract the empty shell from the firing-chamber. The extractor is moved in the opposite direction by a corresponding shoulder n^4 .

15 The trigger is pressed upwardly at its front end by a spring O . Its lower end is provided with lugs o , which slide along the guides in the casing, and the trigger is prevented from being operated when the slide is out of its forward position, as the lugs embrace the guide-rail d^2 and the trigger cannot turn on its pivot. The front end of the guide-rail is, however, notched at o' , so that the lugs can move freely and the trigger can be properly operated.

In Fig. 3 the mechanism is shown retracted, the trigger-guard slide being held back against the force of the spring G^3 by the hand which grasps the trigger-guard. As will be observed, the abutment L is depressed out of the path of the breech-bolt and the firing-pin is cocked. If now the hand be released, the spring forces the trigger-guard slide upwardly and forwardly along its inclined guides, and the lug or stud g' , which extends into the slot in the downwardly-extending arm K' of the bolt, moves the bolt forwardly and shoves the cartridge home into the firing-chamber, the extractor being caught by the rim of the cartridge and by the shoulder n^4 of the bolt and carried into the position shown in Fig. 4. After the cartridge is driven home by the bolt the lug g' enters the inclined slot in the arm K' and the trigger-guard slide moves forwardly a short distance without moving the bolt. By this movement the hooked end of the slide assumes a position in front of the downwardly-projecting arm of the sear, as shown in Fig. 6, and the upper end of the trigger engages with the sear, as shown in the same figure. A bridge-piece x of the bolt is arranged immediately beneath the front end of the sear and prevents the front end of the slide from engaging with the sear should it tend to do so. While the lug g' is moving in the inclined portion of the slot in the arm K' the lug b^2 passes along the inclined groove and slot g^3 , and the abutment L is moved into position behind the breech-bolt and in front of the finger-piece M' of the firing-pin, as shown in Figs. 2 and 4. The gun is then in firing position, and as soon as the trigger is pulled the sear is released from the shoulder m^3 and the cartridge is discharged. By then moving the trigger-guard slide against the force of the spring G^3 the

gun may be recocked and recharged, as will now be explained. The trigger-guard is first moved a short distance without moving the breech-bolt. During its movement the lug g' rides along the inclined slot in the arm K' and engages with the downwardly-projecting arm of the sear, draws the firing-pin backwardly, moves the sear on its pivot, and cocks it by causing its front end to engage with the shoulder m^3 . While the gun is being cocked and before the bolt is moved backwardly the abutment L is withdrawn from behind the bolt by the devices before described. After the gun has been cocked and the abutment $8c$ withdrawn the lug g' engages with the vertical portion of the slot in the arm K' , and the breech-bolt is drawn backwardly. At first it does not move the extractor N ; but as soon as the bolt has moved a sufficient distance the shoulder n^3 engages the heel of the extractor. The shell is withdrawn and is ejected by the top cartridge in the series, which is fed upwardly into position to be shoved home into the firing-chamber. The backward movement 90 of the breech-bolt is stopped when the arm K' comes against the abutment L . When the last cartridge has been inserted into the upper end of the holder in line with the firing-chamber, the carrier d^4 will bear at its front end against the shoulder b and at its rear inclined end z bear against the catch F . After firing the last cartridge and when the breech-bolt has been drawn back the catch F will be disengaged by the incline z on the rear end of the carrier, the shoulder z' will engage the cross-piece e^3 of the case, and the case with the extracted empty shell will both be ejected upwardly from the receiver. Immediately afterward the shoulder z^2 engages the front end of the breech-bolt and locks it back, holding it against the force of the spring G^3 of the trigger-guard slide. It is obvious that the breech cannot be closed until the carrier is disengaged from the bolt. A new packet of 110 cartridges may be inserted in the manner before explained.

When the gun is used as a single-loader, the table d^4 bears at all times at its front end against the shoulder b . Its rear end bears 115 against the front end of the breech-bolt when it is retracted. By the insertion of a single cartridge the carrier is depressed, disengaged from the breech-bolt, and the breech-bolt shoots forward, inserting the cartridge into 120 the firing-chamber.

The gun may be half-cocked by causing the hooked end of the trigger to engage with the shoulder m^7 on the firing-pin. This may be done by retracting the firing-pin by means of its handle and allowing the hooked end of the trigger to engage with the shoulder m^7 when the breech is closed and when the trigger is free to move on its pivot. When thus half-cocked, the gun cannot, of course, be fired 125 without manipulating the handpiece M' . The breech mechanism cannot be operated, as the

upper lug o is located in the notch o' , and the trigger-guard slide is thus prevented from moving.

My improved trigger mechanism insures great safety in operating the gun. In the first place, as before explained, the trigger cannot be moved except when the breech is closed and the lugs are free to move in the slot o' . If the breech is to any extent open—
10 that is to say, if the slide has moved out of its forward position and the lugs are away from the slot o' —the trigger cannot be moved on its pivot. When the breech is closed and the gun is ready for firing, the trigger when 15 first pulled causes the lower lug o to enter the notch o' , and this prevents any backward movement of the breech mechanism. The continued movement of the trigger causes the lower lug o to pass upwardly into the notch, 20 and then the trigger instantly operates the sear to release the firing-pin.

When there is a packet of cartridges in the gun, it may readily be removed by opening the breech, withdrawing the catch F by means 25 of its handle, and allowing the spring-actuated carrier to raise the packet out of the magazine-chamber. As the packet is thus raised it may be received by the hand of the operator.

30 The mechanism described is simple, efficient, and certain. I have shown and described my improvements in the best way known to me. I have, however, devised other ways of carrying out some features of my invention, but do not deem it necessary to illustrate modifications or obvious changes in details of construction that might be made.

I would state further that some features of my invention may be used in firearms of a 40 different class from that to which they are herein shown as applied.

It will be observed that I am enabled by my improvements to operate the breech mechanism by simply drawing back the trigger-guard, 45 thus making it unnecessary to remove the trigger-hand from the butt-stock or to make any inconvenient motions with the trigger-arm. During the continuance of fire from the magazine the position of the weapon at 50 the shoulder is unchanged. The motions of the hand and arm in firing from the magazine are slight, natural, and easy to a degree which has not been approached in cases where it is necessary to remove the hand entirely from the butt-stock.

55 By the automatic return of the mechanism into position the weapon is prepared for firing practically by only two motions. By locking back the breech-bolt whenever the breech is 60 open, while the magazine is empty, the new charge, whether consisting of a full packet or a single cartridge, may be inserted and the weapon gotten ready for the resumption of fire by a single motion.

65 As a single-loader the weapon requires but three motions for charging and firing. It will be observed, also, that the breech-bolt is locked

and held open when the magazine is empty. The mechanism is thus automatically fixed in position for recharging and at the same time 70 the operator, finding that he cannot proceed, receives notice that a recharge is necessary.

Absolute safety is attained by so arranging the sear that it can be operated only when it is in proper firing position, and the trigger 75 being disconnected from the sear, except when the gun is ready for firing, also contributes to this result.

I claim as my invention—

1. A breech-loading firearm comprising a 80 sliding breech-bolt and a sliding spring-actuated trigger-guard operatively connected with the breech-bolt.

2. A breech-loading firearm comprising a 85 sliding breech-bolt, a sliding spring-actuated trigger-guard, a vertically-sliding abutment, a firing-pin sliding in the breech-bolt, and operative connections between the trigger-guard slide, the breech-bolt, sliding abutment, and the firing-pin.

3. The combination, substantially as hereinbefore set forth, of a reciprocating breech-bolt, a spring-actuated slide, connections between the slide and a downwardly-projecting arm of the breech-bolt, a vertically-sliding 90 abutment having a downwardly-extending arm engaging a groove or guide in the slide, a trigger pivoted in the slide, a firing-pin, and its sear adapted to engage with the trigger.

4. The combination, substantially as hereinbefore set forth, of a longitudinally-reciprocating breech-bolt carrying a sliding firing-pin, a trigger-guard slide moving in inclined guides, a sear carried by the firing-pin and adapted to engage with a hook on the front end of the slide and with a shoulder on the breech-bolt, and a vertically-sliding abutment operated by the trigger-guard slide.

5. The combination, substantially as hereinbefore set forth, of a longitudinally-reciprocating breech-bolt, a spring-actuated firing-pin therein, a sear pivoted to the firing-pin, a trigger-guard slide, connections between this slide and a downwardly-projecting arm of the breech-bolt, a vertically-sliding abutment operated by the slide, and a trigger adapted to engage with the sear and with a shoulder of the firing-pin.

6. The combination, substantially as hereinbefore set forth, of a breech-bolt, a reciprocating firing-pin, a sear carried by the firing-pin, and a trigger adapted to engage with the sear and with a shoulder of the firing-pin.

7. In a breech-loading gun, the combination of a longitudinally-reciprocating breech-bolt, and an extractor mounted in a recess in the receiver and provided with a heel extending into a recess in the breech-bolt and moved by shoulders at opposite ends of the recess, the arrangement being such that the breech-bolt may move to a certain extent without moving the extractor.

8. In a magazine-firearm, the combination of a reciprocating breech-bolt, means for feed-

- ing successively a series of cartridges vertically directly into the axial line of fire and into the path of the breech-bolt, and a spring-actuated slide connected with the breech-bolt for 5 forcing it forward to shove the cartridge along the axial line of fire into the firing-chamber.
9. In a magazine firearm, the combination of a receiver open at top and bottom, a detachable automatically-expelled cartridge case or 10 holder, means for feeding successively a series of cartridges vertically directly into the axial line of fire and into the path of the breech-bolt, and a spring-actuated trigger-guard slide connected with the breech-bolt to 15 shove the cartridge along the axial line of fire into the firing-chamber.
10. The combination, in a magazine-firearm, of a spring-actuated carrier located in a magazine-chamber below a receiver open at top 20 and bottom, and a cartridge case or holder the upper end of which is arranged in the receiver and has an opening or chamber into which the cartridges are successively fed and through which the breech-bolt passes.
11. A magazine-firearm comprising a reciprocating breech-bolt and a cartridge case or 25 holder having its upper end arranged in the receiver and having a chamber open at front, rear, and bottom, but closed at top, into which the cartridges are successively fed and through which the breech-bolt passes.
12. A magazine-firearm comprising a cartridge case or holder having a chamber at top into which the cartridges are successively fed 30 and through which the breech-bolt passes, a spring-actuated carrier, and a catch engaging the cartridge-case to hold it in position.
13. In a magazine-firearm provided with a receiver open at top and bottom, the combination 35 of a reciprocating breech-bolt and an automatically-expelled cartridge case or holder having a chamber through which the breech-bolt passes.
14. A cartridge case or holder open at each 40 end and at bottom, provided with grooves for the rims of a series of cartridges and having a chamber at the top adapted to receive a reciprocating breech-bolt.
15. In a magazine-firearm having a receiver open at top and bottom, the combination of a longitudinally-reciprocating breech-bolt, a detachable vertically-moving cartridge case or holder, a catch for retaining the holder in the magazine-chamber, a cartridge-table which engages with the catch to release it 45 and permit the cartridge-holder to be automatically expelled, and a spring which is operatively connected with the table and which forces it upwardly to feed the cartridges successively to disengage the catch and to engage with the cartridge-holder to expel it, substantially as set forth. 55
16. In a breech-loading firearm, the combination of a spring-actuated breech-bolt and a spring-actuated cartridge-table engaging the 60 breech-bolt to hold it in its retracted position against the force of its spring. 65
17. In a magazine-firearm, the combination of a longitudinally-reciprocating breech-bolt, means for reciprocating it, a cartridge-table, 70 means for permanently connecting it to the gun in the magazine-chamber, and means for moving the table into engagement with the breech-bolt to hold it in its retracted position, substantially as set forth. 75
18. In a magazine-firearm, the combination of a cartridge case or holder, a catch engaging therewith, a carrier adapted to disengage the catch from the case and provided with a shoulder to engage the breech-bolt to lock it 80 back after the ejection of the last cartridge-shell.

In testimony whereof I have hereunto subscribed my name.

FRANKLIN W. LANTZ.
